UNITED STATES PATENT OFFICE.

WILHELM GRAAFF, OF BERLIN, GERMANY.

ICE-MAKING AND REFRIGERATING MACHINE.

1,097,312.

Specification of Letters Patent.

Patented May 19, 1914.

Application filed September 26, 1911. Serial No. 651,393.

To all whom it may concern:

Be it known that I, WILHELM GRAAFF, merchant, a subject of the German Emperor, and residing at 17 Linkstrasse, Berlin, W. 5 9, in the Kingdom of Prussia, Germany, have invented certain new and useful Improvements in Ice-Making and Refrigerating Machines, of which the following is a specification.

10 The present invention relates to ice-making and refrigerating machines.

The refrigerator comprises a condenser-evaporator in a container, which holds freezing cells, an ice-safe, one or several refrigerating boxes or the like and is filled with a medium such as a non-freezing brine adapted to transmit the cold from the condenser-evaporator to the freezing cells, the ice-safe or the like. Into this cold transmitting 20 medium the condenser-evaporator of the ice-making machine may be completely submerged. It is, however, more convenient and advantageous, especially with revolving machines to partly immerse the condenser-evaporator into the cold-transmitting medium, so that in consequence of its rotation it will both agitate this liquid and also carry with it in an upward direction a part 25 of the medium taken from the upper, warmer portions, and that the raised part of the medium will spread over the surface of the condenser-evaporator whereby its temperature will be greatly reduced. On again reaching the remaining, warmer portion 30 of the non-freezing medium, this cooler portion will thereupon sink down to the bottom and force the warmer portion upward. This warmer portion is in due course carried around by the revolving condenser-evaporator and cooled. By this means a 35 regular circulation of the cold-transmitting medium or brine is produced, which will greatly promote the ice-making and refrigerating process. For facilitating the raising 40 of the warmer portions of the cold-transmitting medium by the condenser-evaporator, the latter may be provided with webs, buckets or the like.

In the accompanying drawing a constructional form of the present invention is exemplified.

Figure 1 is a plan of the arrangement partly in section, the cover being removed; Fig. 2 is a section along the line A—B in Fig. 1, with the cover in place.

In this drawing *a* is the condenser-evapo-

rator of an ice-making machine, which condenser-evaporator for the purpose of promoting the process within and without, consists of a number of hollow lenticular elements in communication with each other forming a closed vessel which at one end communicates with a cylindrical boiler or generator-absorber *n*, and with which it is made to rotate around a common axis. The 60 condenser-evaporator *a* is inclosed in a structure, which is composed of a container *b* and a lid or cover consisting of two parts *c* and *d*. The lid sections *c* and *d* may be so arranged, that each of them can be separately opened or removed. The part *c* may, however, be coupled by means of a hinge *e* to part *d*, as shown in Fig. 2, and part *d* coupled by means of a hinge *f* to the container *b*. The whole casing *b*, *c*, *d* is of 70 course, insulated with a material of low heat conductivity or made entirely of such a material.

In the container *b* are arranged removable freezing cells *g* in any suitable manner, 80 number and shape. In the drawing they are shown in the shape of flat boxes, so as to allow of producing ice in form of slabs in order that blocks of ice may be obtained by combining several such slabs. The cells *g* 85 rest with beaded rim on ledges *h* provided in the container *b*. According to the shape of the freezing cells these may, however, also be arranged in the container *b* in any other manner allowing of their easy removal.

In place of the cells *g*, a large box, adapted to carry provisions and beverages, may be placed in the container *b*, so that it rests on the cross ledges *h* by means of a flanged rim, 95 hooks or the like. Such a box would preferably be made open at the top or with a removable lid, like lid *c*, so as to allow of an access to its interior by lifting the lid.

The container *b* is filled to a suitable 100 height with a cold transmitting medium *i*, a not easily freezing brine for instance. This liquid or brine surrounds the cells *g*, in the container as far as necessary. The condenser-evaporator *a* is, however, only 105 partly immerged into the solution, so that it will carry up by adhesion during its rotation, a part of the said liquid from the warmest portions of the latter and thereby cooling the raised liquid in the manner hereinbefore described. This cooling effect may 110 be still further increased by providing the

condenser-evaporator with buckets *k*, which are arranged between the lenticular elements of the condenser-evaporator *a* and may project somewhat beyond its periphery.

5 If the machine is to be used as an ice- or refrigerating safe, one of the side walls of the container *b* has an opening, which is made closable by a door and a tight fitting box, projecting into the container *b* is inserted in this opening, so that the articles to be cooled may be introduced through the opening in the wall of the container *b* into the inserted box.

In practice the invention will be carried 15 out in the following manner: The condenser-evaporator *a* during the heating period of the machine is taken away from the container *b* and placed on a special stand, while the heating of the generator-absorber and 20 the cooling of the condenser-evaporator *a* is accomplished by means of a special cooling water. If, however, it should be desired to leave the condenser-evaporator in the container *b* even during the heating period, the 25 container must first be filled with cold water, which water, at the end of the heating period, must be drained off, and the container *b* will thereupon be filled with the cold transmitting medium. A continuous working of 30 the process is not possible, the device operating intermittently.

I claim:

1. In an ice making machine, the combination with a rotating generator-absorber 35 of a rotating condenser-evaporator in communication therewith, said condenser-evaporator comprising a plurality of intercommunicating lenticular elements arranged side by side, a plurality of buckets on the outside

of said condenser-evaporator between the 40 lenticular elements; a container for a cold transmitting medium, said condenser-evaporator being inclosed in said container and partly immersed in the cold transmitting medium, and a receptacle for the material 45 to be cooled within the container immersed in said cold transmitting medium.

2. In an ice making machine, the combination with a rotating generator-absorber, of a rotating condenser-evaporator in communication therewith, said generator-absorber and condenser-evaporator constructed to permanently confine a refrigerant, said condenser-evaporator comprising a plurality 50 of intercommunicating lenticular elements 55 arranged side by side, a plurality of buckets on the outside of said condenser-evaporator between the lenticular elements; a container for a cold transmitting medium, and a lid completely closing the container, said condenser-evaporator being inclosed in said container and partly immersed in the cold-transmitting medium, and a receptacle for the material to be cooled within the container immersed in said cold transmitting medium, 60 said refrigerant being evaporated by means of the external flushing of the condenser-evaporator by the said medium when carried around by said buckets, whereby a cold current is generated in the cold transmitting 65 medium from said condenser-evaporator to said receptacle for cooling said receptacle.

In testimony whereof I affix my signature in presence of two witnesses.

WILHELM GRAAFF.
